UNITED STATES PATENT OFFICE.

CLIFTON CHISHOLM, OF CLEVELAND, OHIO, ASSIGNOR TO THE AMERICAN MULTIGRAPH COMPANY, OF CLEVELAND, OHIO, A CORPORATION OF OHIO.

MECHANISM FOR ASSEMBLING PRINTING STRIPS.

Application filed August 21, 1922. Serial No. 583,188.

To all whom it may concern:

Be it known that I, CLIFTON CHISHOLM, a citizen of the United States, residing at Cleveland, in the county of Cuyahoga and

5 State of Ohio, have invented a certain new and useful Improvement in Mechanism for Assembling Printing Strips, of which the following is a full, clear, and exact description, reference being had to the accompanying drawings.

This invention relates to assembling printing members in the nature of embossed strips upon a suitable holder or chase, and the general object is to provide a simple efficient 15 mechanism capable of quickly positioning such embossed strips upon the chase and for advancing the strip holder quickly to present successive lines for additional strips.

An example of the use of this invention 20 is in conjunction with a part of the device shown, described and claimed in the application of William John Demming, Serial No. 583,192, filed October 21, 1922. The present invention includes an improvement or addition to said Demming machine, whereby I am readily enabled to removably support a flexible printing form, which I term a blanket or chase, having raised projections adapted to receive the embossed strips and 25 carry the same about an arcuate segment. Such a segment may correspond in general dimensions with the drum of a multigraph, whereby the blanket or chase when carrying the strips may be placed about the multigraph drum or any similar device, to print the matter carried thereby. More specific 30 objects include the convenient arrangement of a segment adjacent to the means for advancing the embossed strips thereto from the embossing machine, and for convenient advancing or turning of the segment to present successive lines opposite the channel from which the embossed strips are delivered to the holder.

40 A further object is to provide a simple device for accurately aligning the strip holders on the blanket with the channel for leading the strips thereto by means coacting with each strip holder as it is presented to the channel, whereby accuracy of alignment of the channel with the successive strip holding means is assured.

The above and other objects will become more apparent in connection with the fol-

lowing description which relates to the 55 drawings and the essential characteristics are summarized in the claims.

In the drawings Fig. 1 is a front elevation of the advancing and line positioning mechanism equipped with my arcuate segmental carrier mounted upon the strip delivery mechanism comprising the invention of Demming as disclosed in the application above referred to, parts of this view being broken away for clearness; Fig. 2 is a plan view of the same, parts of the segmental carrier being sectioned for clearness; Fig. 3 is an enlarged sectional elevation of a portion of the segmental carrier and its operating mechanism and showing its relation to 70 the strip advancing mechanism; Fig. 4 is a fragmentary vertical section showing the segment and strip carrier or form with the positioning and advancing mechanism; Fig. 5 is a fragmentary front elevation of the 75 strip carrier or blanket showing the strip being positioned thereon; Fig. 6 is a fragmentary sectional detail showing the means for operating the member engaging and operating the segment.

80 Referring to the drawings by the use of reference characters, I will first describe the operation of the essential parts the Demming mechanism referred to with which my invention is here shown as associated. 1 85 indicates the end of a frame of a suitable embossing machine for making the type characters on strips or ribbons of metal and forming laterally turned flanges by which they may be held on the printing form. Mounted on this end frame 1 is a main frame for a longitudinal slide bracket 5, and a bracket 6 forming bearings for hand operated lever 10 which through gearing, to 90 be described presently, operates a lever 20 95 which moves the slide along the slide frame 5 to operate the type strip engaging hook 25, another strip advancing means moving the strip along the channel toward the carrier.

100 Instead of the vertical slide bracket such as shown in the Demming application referred to, for carrying flat plates or the like, I provide an extension 7 on the main frame carrying a bearing bracket 8 for a shaft 105 30 on which the type carrying segment 35 is mounted. In the Demming mechanism, the embossed strips are moved along a guide

indicated at 4, to a pair of rolls 9 mounted on shafts 11 and driven in unison by means of a pair of meshing spur gears 12, while one of these shafts is driven from a suitable source of power, not shown.

The rolls 9 are formed with pairs of opposed flanges, one pair being adapted to engage the forward sides of the strip outside of the zone of the type and the other 10 being adapted to engage the rearwardly turned flanges of the strip.

Such a strip is designated S, the type characters are indicated thereon and it is provided with flanges S¹ shown particularly 15 in Figs. 3 and 4. A suitable channel leading from these rolls is formed at 15 (Fig. 2) with which cooperates a hook 16 on a slide 17, moved by a lever 18 pivoted through a link 19 to a bracket member 21 20 in turn carried by a bracket member 22 mounted on the main frame and serving to support the roller shafts 11. The lower end of the lever 18 projects into alignment with a slide 110, which has a projection 115 25 adapted to move this lever when the main slide 40 is moved under the influence of the hand lever and lever 20. This hand lever 10 is shown as geared to a pinion 31 and gear 32 on a short shaft 33 rigid with 30 the lever 20, these gears being enclosed by a suitable cover 34. The lever 20 is connected by a link 36 to the slide 110 as shown in Fig. 3. In one edge of this slide 110 35 is a slot 111 into which depends a pin 112 carried by a bar 113 secured on the lower end of the upright rock shaft 26. Accordingly, when the slide 110 is moved it rocks the shaft 26 and the hook 25 it carries to the limit of its movement and then shoves 40 the slide 40 along its slideway 5 so that the hook 25^a may come into position to engage the left hand end of the delivered strip.

As the strip progresses through the rolls 9 and passes free therefrom it stands in a channel 15 in a position where its end may be engaged by the hook 16. A movement 45 of the levers 10 and 20 then actuates the slide 40 moving it to the left and swinging the lever 18 moving the slide 17 and hook 50 16 to bring the strip along the channel 15 to a position where it may be engaged by the shoulder 25^a of the hook 25. Subsequent reverse position of the levers 10 and 20 moves the slide 40 to the right, delivering 55 the strip from the guide way 15 and positioning it upon the chase or carrier as shown in the drawings.

Fig. 4 shows at 25^b a hook, a right hand extension of the lever 25. This hook is useful to shove the strip in the segment backwardly to properly position it, the hook tending to swing toward the segment when the hand lever is operated in the reverse direction and thus being adapted to come 60 65 into position to engage the right hand end

of the strip on the segment. However, this is a special operation, and, normally on the backward movement of the arm 25 the hook 25^b is idle, being prevented from engaging the strip by the position of the eccentric 118, Fig. 3, on the lower end of the rock shaft 119 carrying a positioning arm 120, this eccentric occupying a slot 121 in the bar 113.

I will now describe the arrangement 75 with which the present invention is more particularly concerned, namely, the segmental carrier and type holder or chase and means for operating it in conjunction with a portion of the Demming mechanism above 80 described.

The segment 35 is preferably constructed to form a partially cylindrical surface carried on a radial arm 38 integral with the bearing member 39 which is secured to the shaft 30. This shaft as previously stated is carried by a bracket 8 on an extension 7, the bracket having bearing members 45 positioning the shaft 30 and therefore the center of rotation of the segment 35 and 90 at the same height and therefore normal to the strip channel 15. The chase or blanket, as stated, is of a flexible nature and I prefer to make it as shown wherein the blanket designated 60 is provided with raised ribs 61 from which are punched partially circular projections in a plane parallel with the general surface of the sheet thereby forming overhanging portions 62 in aligned series or rows, whereby the flanges S¹ of the strips may engage and 95 securely hold the strips in place upon the blanket without interfering with the flexibility. As shown the segment 35 is provided near one edge with a rail and its convex surface is covered by a plate 66 on which rests the flexible blanket 60, which blanket is shown as having an inwardly turned edge or flange 64 adapted to hook over the 100 edge of the rail.

To position this flexible strip carrying sheet, I may use suitable removable clips at the opposite edges of the sheet securely holding it in close contact with the drum while allowing ready removal. To this end I have shown in Fig. 5 spring clips 70 on each loop and having end portions 71 extending through eyelets formed in the plate 60 and having offset spring portions 72 and 115 extending inwardly over a flange which may be formed by the rail 91 of the segment, there being an intermediate raised portion designated 74 which may be grasped to raise the hook portion of the spring, that is 75, out of engagement with the flange on the segment. The hook portions of these springs are so formed that they hold an edge of the blanket or chase 60 in close engagement with the surface of the drum or segment, while the spring portion 72 exerts 120 125 130

a circumferential pull, thus accurately holding and fitting this plate to the surface of the segment.

As the embossed strips or lines are positioned upon the blanket, it is desirable to advance the segment and chase one or more lines and accurately position the flexible lines quickly. To this end I allow the plate 60 to overhang the inner side or edge of the 5 segment 35 and come into close proximity with the end of the strip channel, whereby I may take advantage of the overhang to project a latch plunger 80 having a beveled nose into the groove formed by the ribs 61 10 which by reason of the formation of the type holding projections 62 are accurately central thereof. This plunger is shown as mounted in a socket carrying a spring 82 and formed in a boss 83 on the end of an 15 arm 85, pivotally embracing the shaft 30 and carrying a pin 87 extending through a boss 88 rigid with the bearing member 45. This pin forms a stop or abutment and is held securely in place by a screw 90 through 20 the boss 88. As a means of easily and accurately advancing the plate one line at a time, I have shown a reciprocating lever arm 95 to which is attached an outwardly extending handle 96 projecting past the end 25 of the segment above the channel 15. On the end of the arm 95 is pivoted a friction dog 98, from which extends an upwardly projecting pin 99, which may be operated by a lever 100 pivoted to the handle 96 and 30 adapted to be thumb pressed to govern the engagement of this dog with the inner surface of the segment 35. The dog is shown as pivoted at 101 to the lever 95 and as having a surface 102 normally substantially complementary to the surface of the segment 35, but slightly free therefrom, and as beveled inwardly at 103 to form something of a shoulder which may tightly engage the inner surface of the segment under the influence of the spring 105.

By pressing on the thumb lever 100, the pin 99 is swung rearwardly whereby the friction dog is held free from the segment. Upon release, however, the spring causes 50 the dog to engage the segment as shown in Fig. 3 and by the dotted line position in Fig. 4. In this engaging position an upward movement of the handle 96 and lever 95 causes a corresponding movement of the 55 segment 35.

To cause this movement to be a line at a time, I form limits for the upward and downward movement of the lever 95 by projecting the pin 87 through an opening 107 60 in the lever 95. One side of the opening engaging the pin 87 limits the downward movement of the pin 87, while the upward movement, that is the movement which brings a new line or row of projections in 65 position to receive the strip may be governed

if desired, by the limiting stop formed by an adjusting screw 108.

I claim:

1. The combination with means for delivering a printing strip, of a curved printing form having means for receiving and holding the strip, means for moving the strip from the delivering means onto the form, and means for turning the form about the axis of curvature thereof. 70

2. The combination, with means for delivering printing strips, of a curved form for receiving the strips, means for moving the strips from said delivering means onto the form, and means for turning the form 80 about its axis.

3. The combination with means for delivering a printing strip, of a curved printing form, rows of projections on the form for receiving the strips, and means for successively aligning the strip receiving means with said delivering means by turning the form about its axis of curvature. 85

4. The combination, with means for delivering printing strips, of a curved form 90 for receiving the strips, and means actuated by a step by step partial rotation to present the form to receive successive strips.

5. The combination with means for delivering a printing strip, of a printing form 95 adapted to receive a plurality of said strips, an arcuate carrier for said form, and means for aligning the form with said delivering means and movably supporting the same to permit the form to be partially rotated from 100 one line to another with relation to the delivering means.

6. A guideway adapted for slidably supporting and delivering printing strips, a curved printing form having a strip receiving means, means for carrying the form to present said receiving means in alignment with the guideway, means for turning the form about its axis of curvature to present successive lines while in said position. 110

7. The combination with means for delivering a printing strip, of a curved printing form having means thereon for holding the strips in a series of parallel lines, means for rotatably mounting said form to permit the presentation of successive lines to the delivering means, and means to engage the rear end of the strip and shove it onto the form. 115

8. The combination with means for delivering a printing strip, a curved printing form having means thereon for holding the strips in a series of parallel lines, means for rotatably mounting said form to permit the presentation of successive lines to the delivering means, means for progressing the form and its holder a line at a time, and means for latching the holder with a line in receiving position. 120

9. The combination with means for de- 125

- 5 livering printing strips having inwardly turned flanges, of a curved printing form having a series of projections for receiving said flanges to hold the strip in printing position, and means for latching the projections in alignment with the delivering means including a stationary plunger and a depression on the form definitely positioned with relation to the line.
- 10 10. The combination with means for delivering printing strips, a form member having a series of parallel lines of projections, and means for mounting the form to receive the strips on said projections from the delivering means, means engaging the form itself for latching successive lines in receiving position and accurately aligning the projections.
- 15 11. The combination with means for delivering printing strips, a form for receiving said strips having a line of projections to receive the strip from the delivering means, means for latching successive lines in receiving position and accurately aligning the projections including a stationary member relative to the delivering member and carrying a latch member, the form and latch member having a cooperating projection and depression for accurately positioning the line.
- 20 12. The combination with an arcuate printing form, in the nature of a metal sheet having projections stamped therefrom in rows and having a groove along each row, extending to the edge of the strip, means for delivering printing strips onto said projections longitudinally, means for movably supporting the form to present successive lines to the strip delivering means, and a movable projection accurately positioned with relation to the delivering means and adapted to successively engage in said grooves to align and latch the form.
- 25 13. The combination with means for delivering printing members in the form of strips having inwardly turned flanges, a guideway and means for moving said strips along said guideway, a curved printing form adapted to be used on a rotary press and on which such strips may be removably carried, means for moving the strips onto the printing form from the guideway, and means for turning the form about its axis to present an unoccupied space to receive the strip.
- 30 14. A guideway adapted for slidably supporting printing strips, a curved printing form having strip carrying means therefor, means for supporting the printing form and turning it about its axis to bring said strip carrying means into alignment with said guideway, and means for shoving the strips lengthwise thereof from the guideway onto the form.
- 35 15. The combination with embossed strips each having a single row of characters, of delivery rolls adapted to form inwardly turned flanges on the strips, a rotary printing form having projections for receiving said flanges to mount the strip thereon, a guideway and means for mounting the printing form, said means being rotatable to present said form in alignment with said guideway.
- 40 16. The combination with means for delivering embossed printing strips, of a segmental holder, a flexible blanket adapted to be mounted thereon and provided with rows of projections to receive the strips, means for moving the strips onto the blanket, and means causing a step by step movement of the form about the axis of the segment.
- 45 17. The combination with means for delivering line printing strips, of a printing form to receive the strips, means for moving the strips onto the form and for holding them thereon, means for supporting the form in position to receive the strips, means for removably securing the form in this position, a movable dog frictionally engaging the form for causing a step by step movement of the form to present successive line strip holding means.
- 50 18. In a device of the character described, the combination with means for delivering a printing strip, of a rotatable form having means for holding a series of said strips in parallel lines, a guideway, a slide adapted to move the strips into the form, and means for advancing the form a line at a time a friction dog mechanism operative in one direction and idle in the other for advancing the form.
- 55 19. In a machine of the character described, the combination with opposed continuously rotated rolls adapted to deliver a printing strip, a guideway adapted to receive the strip from the rolls, a segmental printing form, means for moving the strips from the guideway onto the form, and means for turning the form about its axis.
- 60 20. The combination with means for delivering embossed printing strips, of a guideway having means coacting with the edges of the strip, a printing form having a series of aligned projections receiving said edges of the strip, a rotatable segment of a cylinder for supporting the form on its cylindrical surface, means adapted to align said projections with the flanges of the guideway, means for progressing the strip along said guideway and onto the form, and means for sliding the strip in either direction along said projections on the form.
- 65 21. The combination with a printing holder having raised projections connected by corrugated portions of a positioning device adapted to engage successive corrugations.
- 70 22. A holder for printing strips comprising

ing a sheet metal member having on its face raised projections and upwardly projecting corrugations between the projections combined with means on the rear side of 5 the plate to engage one of such corrugations.

23. A form holder for printing strips comprising a plate having parallel rows of projections on its face and upwardly projecting corrugations between the projections, 10 and mechanism adapted to periodically engage in the grooves provided on the rear side of the plate by the corrugations of successive rows.

24. The combination of a flexible blanket having on its face parallel rows of raised 15 projections with corrugations between them, embossed printing strips overlying such rows of projections and corrugations and having flanges engaging beneath the overhanging edges of the projections, and mechanism adapted to engage successively in the grooves made by corrugations of successive lines.

In testimony whereof, I hereunto affix my signature.

CLIFTON CHISHOLM.
